US0D1022948S

(12) **United States Design Patent** (10) Patent No.: **US D1,022,948 S**
Shiraga et al. (45) Date of Patent: ** Apr. 16, 2024

(54) **HEADSET**

(71) Applicant: **Audio-Technica Corporation**, Tokyo (JP)

(72) Inventors: **Tomohiro Shiraga**, Kanagawa (JP); **Chihlung Wu**, Taoyuan (TW); **Shigeo Hara**, Tokyo (JP)

(73) Assignee: **Audio-Technica Corporation**, Tokyo (JP)

(**) Term: **15 Years**

(21) Appl. No.: **29/793,488**

(22) Filed: **Nov. 28, 2022**

(30) **Foreign Application Priority Data**

Jul. 25, 2022 (JP) ..... 2022-015790 D

(57) **CLAIM**

The ornamental design for a headset, as shown and described.

DESCRIPTION

FIG. 1 is a front, top, right side perspective view of a headset;

FIG. 2 is a rear, bottom, left side perspective view of the headset;

FIG. 3 is a front elevational view of the headset;

FIG. 4 is a rear elevational view of the headset;

FIG. 5 is a top plan view of the headset;

FIG. 6 is a bottom plan view of the headset;

FIG. 7 is a left side elevational view of the headset;

FIG. 8 is a right side elevational view of the headset;

FIG. 9 is a front, top, right side perspective view of the headset, shown in an alternate, unfolded, configuration; and, FIG. 10 is a front, top, right side perspective view of the headset, shown in another alternate, unfolded, configuration. Portions of the drawings shown in broken lines form no part of the claimed design.

1 Claim, 10 Drawing Sheets
